Inventor:
George A. Woodman
By J. M. J. Bell Atty.

UNITED STATES PATENT OFFICE.

GEORGE A. WOODMAN, OF CHICAGO, ILLINOIS, ASSIGNOR TO WOODMAN RAILWAY SUPPLY COMPANY, OF CHICAGO, ILLINOIS, A CORPORATION OF ILLINOIS.

CAR-TRUCK PEDESTAL.

Application filed September 30, 1925. Serial No. 59,488.

This invention relates to a novel and improved car truck pedestal and more particularly to a novel and improved liner for the pedestal where it comes in sliding contact with the journal box with which it cooperates.

Briefly, my invention comprises a liner made preferably of high carbon steel and arranged to be sprung into position on the inner face of each jaw of a pedestal, where it is retained by its inherent resiliency. Spot welding may be resorted to in order to more firmly secure the liner in place but in any event the liner may be easily removed and replaced as it becomes worn.

In the accompanying drawing in which I have shown a selected embodiment of my invention

Fig. 1 is an elevation of a car truck having my invention embodied therein.

Fig. 2 is an enlarged elevation of a pedestal to which my improved liners are attached.

Fig. 3 is a section on the line 3—3 of Fig. 2.

Fig. 4 is a section on the line 4—4 of Fig. 2.

Fig. 1 shows a well known type of truck comprising journal boxes which are connected by the equalizer 2 which supports the bolster 3 in the usual manner, and to which are secured pedestals 4. Each pedestal is provided with jaws 5 which have sliding engagement with a journal box, the journal box being received between the jaws. This is a well known form of car truck construction.

In order to prevent excessive wear I provide the inner surface of each jaw 5 with a hard steel liner 6. Preferably the inner surface of each jaw is recessed as indicated at 7 to form shoulders with which the top and bottom of the liner may engage, and the sides are also recessed as at 8 to furnish shoulders for engagement of the rear edges 9 of the liners. It will be seen that each liner is in the form of a channel having the rearwardly extending ends 9 and the intermediate portion 10, the latter forming the wearing surface. Preferably the liner is made of spring high carbon steel, which not only will have a long life but which will also have an inherent resiliency. I prefer to make use of this resiliency to hold the liner

in place. This may be accomplished by initially bending the ends 9 of the channel towards each other slightly more than shown in Fig. 4, so that it will be necessary to spring them slightly away from each other in order to get the liner in place. Any other manner of making use of the resiliency of the liner may be employed.

While in actual practice I have found that liners constructed as above will stay in place it may be found desirable to spot weld the liners in position as at 11. Of course, I do not desire to limit myself to spot welding as the liners may be welded throughout the length of their edges. This welding, however, should not be carried to such an extent that the liner may not be readily removed from the pedestal. Removal may be readily accomplished by striking the liner from the rear through the opening 12 in the jaw of the pedestal. The liner is recessed as shown at 13 to permit the passage of the equalizer 2, which, as is well known in the art, rests upon the top of the journal box.

From the above it will be apparent that I have devised a car truck pedestal embodying a liner which may be easily put into position and as easily removed therefrom. After having been put in place the ends 9 prevent movement of the liner in a direction parallel to the axle of the car wheel and the shoulders 7 prevent vertical movement. Movement toward the journal box is prevented by the presence of the journal box and therefore, the liner is held in place. The welding, when employed at all, is merely an added precaution.

I am aware that changes in the form, construction and arrangement of parts may be made without departing from the spirit and without sacrificing the advantages of the invention and I reserve the right to make all such changes as fairly fall within the scope of the following claims.

I claim:

1. A car truck pedestal comprising jaws adapted to receive a journal box therebetween, and a liner on the surface of each jaw next to the journal box and made of channel form embracing the jaw, said liner being made of spring material and held in position by the resiliency thereof and by means arranged on the side of the jaws for restricting lateral movement of the liners.

2. A car truck pedestal comprising jaws adapted to receive a journal box therebetween, the surface of each jaw next to the journal box being recessed to form shoulders, and a liner received within said recesses and retained in position by said shoulders and by the resiliency of the material of which the liner is made.
3. A car truck pedestal comprising jaws adapted to receive a journal box therebetween, liners on the jaws, integral shoulders on the jaws against which the top and bottom of the liners abut to prevent up and down movement of the liners on the jaws, and means arranged on the sides of the jaws

for confining the movement of the liners laterally.

4. A car truck pedestal comprising jaws adapted to receive a journal box therebetween, channel shaped liners on the jaws, 20 and integral shoulders on the jaws against which the inner edges of the liners abut.

5. A car truck pedestal comprising jaws adapted to receive a journal box therebetween, channel shaped liners on the jaws, 25 and integral shoulders on the jaws to engage the top and the bottom and the inner edges of the liners.

GEORGE A. WOODMAN.
